RICHARD F. HOYT, OF PHILADELPHIA, PENNSYLVANIA, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,280,228.

Specification of Letters Patent.

Patented Oct. 1, 1918.

Application filed November 2, 1914. Serial No. 869,720.

To all whom it may concern:

Be it known that I, RICHARD F. HOYT, a citizen of the United States, residing in Olney, Philadelphia, in the county of Philadelphia and State of Pennsylvania, have invented certain new and useful Improvements in Combined Type-Writing and Computing Machines, of which the following is a specification.

10 My invention relates to computing machines, and is herein described and illustrated as applied to a combined typewriting and computing machine of the Underwood-Hanson type wherein the numeral keys of 15 the typewriter set up *seriatim* on rack bars a series of numbers and said numbers are later carried into a gang of computing wheels. Such machines are usually provided with means whereby they may be caused to 20 subtract, and also with means whereby their computing devices may be driven by an electric motor, said motor driving a general operator for carrying the set-up numbers into the wheels. The machine is further 25 illustrated as one in which the subtraction is done by setting up numbers complementary to those normally set up and then driving the wheels in adding direction.

According to my invention, the ordinary 30 tabulating column stops of the Underwood machine may be utilized to automatically set the mechanism for subtraction and also automatically start the general operator. The setting of the mechanism for subtraction 35 usually takes place at the beginning of a computation, while according to my invention, the starting of the general operator advantageously takes place at the beginning of the return movement of the typewriter carriage, thus allowing ample time for the numbers to be carried into the computing wheels without interfering with other operations. To obtain these results, I have found it advantageous to provide the usual column 40 stops of the Underwood typewriting machine with a dog or dogs, one of said dogs being adapted to cooperate with a starting device for the general operator on a return movement of the typewriter carriage, while 45 if it is desired to do subtraction, said stop may also be provided with a dog which is

effective on the forward movement of the typewriter carriage to set the mechanism to subtraction. One result is that the setting of a single stop determines the computing 55 position of the carriage, and insures that the general operator will cause the numbers to be computed even if the carriage is returned immediately after the number is written. 60

Other features and advantages will hereinafter appear.

In the accompanying drawings,

Figure 1 is a sectional side view of a combined typewriting and computing machine 65 of the Underwood-Hanson type showing my invention as applied thereto.

Fig. 2 is a rear view of a portion of the same showing rather diagrammatically a column stop effective on its return move- 70

ment.

Fig. 3 is a diagrammatic perspective view showing a dog on which the column stop dog is effective, together with its coöperating parts. 75

Fig. 4 is a fragmentary perspective view of the upper part of Fig. 2 together with some adjacent parts.

Fig. 5 is a rear view of Fig. 1.

Fig. 6 is a view similar to Fig. 2, but 80 showing the typewriter carriage moving in the opposite direction.

In the Underwood typewriting machine, alphabet keys 1 and numeral keys 2 depress key levers 3 to swing type-bars 4 by bell-crank 5 upwardly and rearwardly against a platen 6, so as to cause the types 7 to print on a work-sheet on said platen. As the type-bars 4 approach the platen, they engage a universal bar 8 by heels 9, so as to operate 90 dogs 10 to feed the typewriter carriage along in letter-feeding direction. Said carriage is normally under tension of a spring barrel, not shown herein, and said dogs control the movement of the carriage under the 95 tension of said spring barrel through the escapement wheel 11, on which they are effective, said escapement wheel being connected to a pinion 12 working in a rack bar 13, said rack bar being pivoted in the usual 100 manner to a carriage 14 on which the platen 6 is mounted.

In order to rapidly position the typewriter carriage at any desired point, tabulating keys 15 are provided on the front ends of the key levers 16, the rear ends of the said key levers operating plungers 17, which at their upper ends, when the appropriate tabulating key 15 is depressed, project the top 18 of the plunger in the path of a column stop 19 on the typewriter carriage.

- 10 Whenever any one of the tabulating keys 15 is depressed, its plunger 17 is effective to release the typewriter carriage from the escapement dogs 10, this being done by a small universal bar 20 which by means of the usual 15 connections not material to the present invention, lifts the rack bar 13 out of the pinion 12, thus freeing the carriage from the control of its escapement dogs 10 and permitting said carriage to be drawn along 20 until it is arrested by its column stop, which is intercepted by the upper end 18 of a projected plunger 17, said upper end therefore being a counter-stop for the column stop 19. The column stops 19 are settable on the usual 25 rack bar 21, which is fast on the typewriter carriage, so that a column may be selected at any point in the travel of said carriage.

The Underwood-Hanson combined typewriting and computing machine also includes computation members 22 on which numbers are set up by pins 23 thereon, there being a separate pin for each digit on each rack bar, and when the numbers are so set up, the numbers are carried into the computing wheels 24 by a general operator. To thus carry them, the general operator includes a cross bar 25 which reciprocates backwardly and forwardly in such a way that on its forward stroke it drives forward 30 the computation members or rack bars 22 by striking any depressed pin and carrying forward the various rack bars to an extent dependent upon the pin depressed on the individual rack bar.

40 45 The pins are restored on the return stroke of the general operator, and the rack bars carried back by means not material to the present invention. The computing wheels 24 are not turned on said return stroke because of pawl-and-ratchet connections, not shown herein.

In order to set up the pins on the rack bars, the numeral keys 2 are provided with pendants 26 each of which, when its key is 50 depressed, descends and strikes its rock arm 27 on a rock shaft 28, so as to operate its pin-setting linkage, of which there is one for each numeral key.

Said linkages, when the keys are depressed, operate idly outside of the adding zone. Inside the adding zone, however, the rack bars are lifted *seriatim*, so as to bring the pins thereon within the range of the pin-setting bars 29 of said pin-setting linkages, 55 with the result that on the bar which has

been lifted for the moment, the pin will be depressed corresponding to the pin-setting bar 29, which is thus operated.

To thus raise the rack bars 22, there is provided a dog 30 on the typewriter carriage, which, as the carriage travels along, rides under and raises one after another, the front ends of jacks 31 so as to depress the rear ends 32 thereof, causing said rear ends to 70 depress rods 33, said rods being in the usual manner, not shown herein, connected to lift the rack bars 22, there being one rod 33 and correspondingly one jack 30 for each rack bar. The mechanism above briefly referred to is fully shown and described in the 80 British Patent No. 3390 of 1912.

Since the typewriter carriage travels to the left while numbers are usually inserted beginning on the left-hand computing rack bar or computing wheel, a transposition device 34 fully described in said patent is provided between the rods 33 and the rack bars 22, so that as the typewriter carriage travels toward the left, it will lift the computation bars 22 one after another, beginning with 90 the left-hand one.

In order to effect subtraction, the machine is shown as including a complementary subtraction device, of which the control centers in a bar 35. When said bar is made effective, as is sometimes done, by a spring 36, it moves rearwardly, thus causing a cross bar 37 universal to the rock shafts 28 to shift said rock shafts forwardly, releasing the pin-setting linkages from the addition rock arms 38 by which they are normally operated, and causing them to be engaged by subtraction rock bars in the manner disclosed in the application of Ogden Minton, No. 797,714, filed October 28, 1913, at the same time, 100 their "9" pins are set on the computation bars 22. This brief description includes some of the principal operations in subtraction-setting, but said subtraction-setting is not described in detail herein in order to 105 simplify the disclosure. The subtraction bar 35 is usually kept from being made effective by a dog 39, which normally engages a slot 40 in said subtraction bar.

This dog 39 is adapted to be moved to ineffective position by the travel of the typewriter carriage. Many of the specific connections for doing this are not material to the present invention, but they include a rocking bail 41 which is journaled on a rod 42 and comprises a rock arm 43 which is connected to a link 44, said link being moved upwardly at a given point in the travel of the typewriter carriage.

The upward motion of the link 44 withdraws a restraining bar 44* which normally holds the subtraction pawl 39 in effective position. When the subtraction pawl 39 is thus moved, the spring 36 pulls the bar 35 to the right in Fig. 1, and converts the mech- 125 130

anism to subtraction. When the general operator is started by means to be presently described, the cross bar 25 of the same engages the lug 98 projecting downwardly 5 from the bar 35 and restores said bar to normal position, thus setting the machine again for addition. It will be perceived from said construction that at each operation of the general operator, the computing 10 mechanism either changes its state, or operates without a change of state, depending on whether or not the pawl 39 has been operated, and this in turn depending on whether or not the link 44 has been moved. The 15 link 44 is thus moved upwardly to cause subtraction by means of a dog 45 forming part of a tabulating stop, said dog, as best seen in Fig. 4, being illustrated as the inner extension of a dog 46, which will be described later. Said dog 45 is formed as an extension of the column stop 19, and therefore whenever the column stop is set at an appropriate position on the rack bar 21, the dog 45 will, of course, be at the same position. This dog 45 is arranged to cooperate with a pawl 47 during the travel of the typewriter carriage in letter-feeding direction, which, in Fig. 5, being a rear view, is to the right. 20

If the typewriter carriage is brought to the computing column by the tabulating device, the pawl 47 will be struck by the dog 45 just before the column stop 19 arrives over the highest decimal counter stop of the 25 tabulating device. This sets the mechanism to subtraction therefore at a point just before the highest digit of a number could be written in the computing column. The pawl 47 for accomplishing this, is located 30 on a lever 48 pivoted between its ends at 49, so that the pawl 47 will stand at the proper position with relation to the tabulating stops, and the opposite end 50 of said lever is pivotally connected to the vertical 35 rod 41, which operates the subtraction-setting device. The pawl 47 is mounted on its lever by a headed screw 51, and is held by a spring 52 which constantly tends to hold it in effective position, but permits said pawl 40 to be swung out of the way when the carriage is brought back on its return stroke, on which stroke the carriage carries the column stop 19, as viewed in Fig. 4, to the left. In order to prevent the pawl 47 from 45 being swung out of the way during the forward motion of the carriage, there is provided a set screw 53 which limits the throw of said pawl to the right, as viewed in Fig. 4. The restraining bar 44 is restored to its 50 effective position by the general operator when actuated at the end of a subtraction operation.

After a number has been written and set up on the computation pins 23, the numbers 55 have to be carried into the computing

wheels, as described above. In the present mechanism, the numbers are so carried by a motor 54 which is effective on the general operator, which has been described above as including a cross bar 25. This motor is 70 effective through a slide 55 through connections which will be described below, said slide engaging the general operator by means of a yoke 56 fast on one of the side bars 57 of the general operator. Said motor is normally ineffective on said slide, but is made effective thereon by a dog 46 forming the other extension of the column stop 19 mentioned above. For this purpose, the extension 46 cooperates with a pawl 58 80 which is advantageously set to be operated by said dog as the typewriter carriage feeds from the units digit place in the adding column.

In the escapement usually employed in 85 the Underwood machine, when a number is written in said units place, the carriage feeds one letter-space more as the numeral key rises, and therefore the pawl 58 is advantageously placed and designed so as to 90 be operative in this letter-space, thus avoiding any complications which might otherwise result if the typist returned the typewriter carriage to begin a new line immediately after writing in said units digit 95 place. The pawl 58 is mounted on a lever 59 pivoted between its ends at 60, and in order that the pawl may permit the typewriter carriage to return idly with respect thereto, said pawl is pivoted on the lever at 100 61, it being normally held in effective position by means of a spring 62, which holds it against a set screw 63. Said set screw is provided with a jam-nut 64 so that it may be locked in position on its lug 65 on the 105 lever 59. This pawl is effective only on the return movement of the typewriter carriage, and on such return movement, its cam face 66 enables the dog 46 to force said lever downwardly, thereby lifting the opposite 110 end 67 of said lever, with the result that a link 68 is drawn upwardly to start the motor 54 and connect the motor to the slide 55.

The link 68 starts the motor by withdrawing the pin 70, which normally holds a 115 clutch 69 open and also holds the motor circuit 71 open. The connection between the link 68 and the pin 70 includes a rocking bail 72 which, when the link 68 is drawn upwardly, frees the control bar 73, which is 120 normally held down by a link 74 pivotally attached to the bail 72. When this control bar 73 is released from the link 74, a spring 75 draws this bar upwardly, thereby depressing the opposite end 76 of the control 125 bar which is on the farther side of its pivot 77, so that said control bar moved downwardly the plunger 78 by a follower 79 thereon, in the manner described in the application No. 797,714 aforesaid. This plun- 130

ger may be manually operated by means of a finger-piece 80, and when depressed, swings a lever 81, so as to lift the pin 70 at the opposite end thereof to render effective 5 the clutch and cause the motor to drive the general operator. The clutch is of the type shown in the application of Frederick A. Hart, No. 650,700, filed September 22, 1911, and patent to J. N. Thornton, 1,146,371, 10 July 13, 1915, wherein the circuit 71 of the motor is carried into the clutch so that the clutch not only controls the slide 55, but also controls the circuit driving the motor in the manner described in said application 15 of Hart and in said patent.

The connections between the motor 54 and the slide 55 include the shaft 82 of the motor, which comprises a worm 83 adapted to constantly rotate the worm gear 84 when 20 the motor turns, said worm gear being extended to form a hub 85. This hub is embraced by a cup 86 fast to the central shaft 87, and between the hub 85 and the cup 86 are interposed balls or rolls 88, which are 25 normally held in idle position, but which, when the pin 70 is withdrawn, are carried around by the roll-carrier 89, causing them to be jammed between the cup 86 and the hub 85 with the result that the motor, as it 30 turns the hub of the worm gear 84, will also turn the cup 86. Said cup drives the slide 55 by means of an abutment (not shown).

The rolls 88 are normally held in their 35 idle position by means of the pin 70 acting through a spring 93. The pin 70 also holds in circuit-breaking position, a conductor ring 90 which is interrupted at one point so that when the roll carrier 89 is held by a pin 40 70, the circuit through the conductor ring 90 is interrupted, because the interruption in said ring is then opposite the conductor 91 with which said ring cooperates to form the circuit. When, however, the pin 70 is 45 withdrawn, the conductor ring springs forward under the impetus of the spring 93, thus closing the circuit and starting the motor. This starting of the motor causes the hub 85 to revolve, thereby tending to carry 50 the roll carrier 89 around by friction, there being provided spring-pressed friction studs 92 extending through the roll carrier and bearing against said hub, with the result 55 that the studs carry around the roll carrier whenever the motor turns, unless said carrier is arrested by the pin 70.

It will be seen that I have provided a mechanism in which a single column stop of the ordinary tabulating device determines 60 whether the mechanism shall add or subtract, and also insures that when the typewriter carriage is returned to write a new number, the number set up in the temporary register by the pins 23, will be carried into 65 the computing wheels. This starting of the

motor to carry in the numbers, takes place irrespective of where the column is, and also takes place at a time when there can be no possible interference with any other operation in the typewriting mechanism or computing mechanism. 70

Another advantage is that in machines having several registers (as shown at 95, 96 and 97, Fig. 5), only a single starting pawl 58 is needed, and this will be effective whenever the carriage is returned from any computing zone. The general operator will, therefore, be actuated only while the typewriter carriage is returning. 75

Variations may be resorted to within the 80 scope of the invention, and portions of the improvements may be used without others.

Having thus described my invention, I claim:

1. In a combined typewriting and computing machine, the combination with a traveling carriage and computing wheels, of a source of power, and a member settable on said carriage to cause said wheels to subtract during the forward movement of said 90 carriage and effective during the return movement of said carriage to cause said source of power to cause said wheels to operate. 85

2. In a combined typewriting and computing machine, the combination with computing wheels, a traveling carriage and a source of power, of a member settable on said carriage adapted to cause said source of power to operate said computing wheels 95 during the return movement of said carriage, and dogs forming part of said member and selectively settable to be effective at the beginning of the computing column 100 on the forward movement of said carriage 105 to cause said wheels to subtract.

3. In a combined typewriting and computing machine, the combination with a general operator and a source of power actuating it, of a traveling carriage, a subtraction pawl, a pawl for controlling said source of power, and a single device settable to operate one of said pawls on the forward stroke of the carriage, and the other of said pawls on the return stroke of the carriage. 110

4. In a combined typewriting and computing machine, the combination with a traveling carriage and a tabulating device therefor, comprising stops settable on said carriage for determining computing zones, of a dog forming part of a stop, numeral keys, computing wheels adapted to be turned together to an extent determined by said keys, a motor for so turning said wheels, and 120 means operated by said dog during the return travel of the typewriter carriage through a computing zone for causing said motor to be effective on said wheels. 125

5. In a combined typewriting and computing 130

- puting machine, the combination with a traveling carriage and a tabulating device therefor, comprising stops settable on said carriage for determining computing zones, 5 of a dog forming part of a stop, numeral keys, computing wheels adapted to be turned together to an extent determined by said keys, a motor, a normally open circuit driving said motor, and means operated by said 10 dog during the return of the typewriter carriage through a computing zone for causing said motor to carry numbers into the said wheels.
6. In a combined typewriting and computing machine, the combination with a traveling carriage and a tabulating device therefor, comprising stops settable on said carriage, of a dog forming part of a stop, 15 numeral keys, computing wheels adapted to be turned together to an extent determined by said keys, a motor for so turning said wheels, means operated by said dog during the return travel of the typewriter carriage for causing said motor to be effective on said 20 wheels, a normally open circuit driving said motor, a second dog on said stop, and a device operable by said second dog for causing said wheels to subtract.
7. In a combined typewriting and computing machine, the combination with numeral keys and computing wheels, of a motor for carrying simultaneously the numbers written by said keys into said wheels, a traveling carriage, a tabulating device for 25 positioning said carriage and including a column stop, dogs on one side of said column stop adapted to cause said mechanism to subtract and the numbers to be automatically carried into said wheels, and a dog on the 30 opposite side of said stop adapted to cause the numbers to be carried into said wheels, but ineffective to cause subtraction.
8. In a combined typewriting and computing machine, the combination with a traveling carriage and a plurality of registers for computing, of a general operator for 35 said registers, a power device for driving said general operator, a series of stops for positioning said carriage, and means associated with each stop for causing said power device to operate said general operator at the beginning of the return of the carriage immediately after writing the last digit of 40 a number in any one of the computing columns.
9. In a combined typewriting and computing machine, the combination with a traveling carriage and a plurality of registers for computing, of a general operator 45 for said registers, a power device for driving said general operator, a series of stops for positioning said carriage, and means associated with each stop for causing said power device to operate said general operator at the beginning of the return of the carriage.
- immediately after writing the last digit of a number in any one of the computing columns; said stops selectively settable to determine whether any register shall add or subtract. 70
10. In a combined typewriting and computing machine, the combination with a traveling carriage and computing wheels, of a motor for driving said wheels in unison, a normally open circuit for driving said motor, a tabulating stop for positioning said carriage, and means associated with said stop and controlled thereby for closing said circuit at the beginning of the return of said carriage after writing the last digit of 75 a number. 80
11. In a combined typewriting and computing machine, the combination with a traveling carriage and computing wheels, of a motor for driving said wheels in unison, a normally open circuit for driving said motor, a tabulating stop for positioning said carriage, and means associated with said stop for setting said wheels for subtraction on a feeding movement of said carriage and 85 for closing said circuit at the beginning of the return of said carriage after writing the last digit of a number. 90
12. In a combined typewriting and computing machine, the combination with numeral keys, a series of groups of computing wheels, and a traveling carriage, of a general operator for all said wheels, a motor for driving said general operator, a normally open circuit for driving said motor, 95 tabulating stops for positioning said carriage, and means whereby said stops close said circuit on the return of the carriage from computing in any one of said groups of wheels. 100
13. In a combined typewriting and computing machine, the combination with numeral wheels and a traveling carriage, of a series of decimal stops including a units stop, and a coöperating tabulator stop for 110 positioning said carriage, a power device for doing the computing, and means made effective by said tabulator stop during its return past said units stop for causing the computation. 115
14. In a combined typewriting and computing machine, the combination with a traveling carriage and computing wheels, of a pawl effective in one direction of movement of said carriage to cause said wheels 120 to subtract, and a pawl effective in the opposite direction of movement of said carriage to cause said wheels to be actuated.
15. In a combined typewriting and computing machine, the combination with computing mechanism, of a letter-feeding carriage, a member settable thereon, indexing mechanism for indexing numbers to be carried into the computing mechanism, and a power device for carrying into the comput- 125 130

- ing mechanism the numbers indexed, said settable member being reversible and being provided with means when in either position for controlling said power device for running into the computing mechanism the numbers indexed.
16. In a combined typewriting and computing machine, the combination with computing mechanism, of a general operator therefor, a letter-feeding carriage, a reversible tabulator stop therefor, and means for controlling said computing mechanism as to one state when said tabulator stop is in one position, and controlling said computing mechanism as to another state when said tabulator stop is reversed, said stop acting in one position to change the state through the medium of the general operator.
17. In a combined typewriting and computing machine, the combination with computing mechanism, of a letter-feeding carriage, a member settable thereon, and a plurality of trips for controlling said computing mechanism, said settable member having lugs differently formed on its opposite sides, and adapted when in one position to present one of said lugs to control said computing mechanism through the medium of one of said trips, and acting when in the other position to present the other of said lugs to control said computing mechanism through the medium of both of said trips.
18. In a combined typewriting and computing machine, the combination with computing mechanism, of indexing mechanism therefor, a power device for running into the computing mechanism the numbers indexed, state-controlling mechanism for said computing mechanism, and a letter-feeding carriage, said carriage acting to control the state of said computing mechanism on movement in one direction and to control the activity of said power device when moving in the other direction.
19. In a combined typewriting and computing machine, the combination with computing mechanism, of indexing mechanism therefor, a power device for running into the computing mechanism the numbers indexed, state-controlling mechanism for said computing mechanism, and a letter-feeding carriage, said carriage acting to control the state of said computing mechanism on a letter-feeding movement thereof, and acting on the return movement to control the activity of said power device.
20. In a combined typewriting and computing machine, the combination with computing mechanism, of indexing mechanism therefor, a power device for running into the computing mechanism the numbers indexed, state-controlling mechanism for said computing mechanism, and a letter-feeding carriage for determining the computing
- zone, said carriage acting at the beginning of a computing zone to control the state of said computing mechanism, and acting on the return movement after completing its zonal movement to control said power device.
21. In a combined typewriting and computing machine, the combination with computing mechanism, of a letter-feeding carriage; a member settable on said carriage, indexing mechanism, and a power device for running into the computing mechanism the numbers indexed, said carriage, on a letter-feeding movement, acting through the medium of said settable member to control the state of said computing mechanism, and acting, on its return movement, through the medium of said settable member to control the effectiveness of said power device.
22. In a combined typewriting and computing machine, the combination with computing mechanism, of a letter-feeding carriage for determining the computing zone, a tabulator stop for said carriage, indexing mechanism for the computing mechanism, and a power device for running into the computing mechanism the numbers indexed, said carriage acting at the beginning of each computing zone, as determined by said tabulator stop, to control the state of said computing mechanism through the medium of said stop, and acting on its return movement, also through the medium of said stop, after completing its travel through the computing zone, to control the activity of the power device.
23. In a combined typewriting and computing machine, the combination with computing mechanism, of a letter-feeding carriage; a trip device controlled by the carriage for determining the state of said computing mechanism, indexing devices, and a power device for running into the computing mechanism the numbers indexed, said carriage acting on said trip device to control the state of said computing mechanism on a letter-feeding movement of said carriage, and acting to render said power device effective on the beginning of its return movement.
24. In a combined typewriting and computing machine, the combination with computing mechanism, of a letter-feeding carriage, a trip device controlled by said carriage for determining the state of said computing mechanism, indexing devices, a power device for running into the computing mechanism the numbers indexed, and a second trip device controlled by said carriage for determining the activity of said power device, said carriage acting on said state-control trip on a stepping movement thereof and on said power trip on the beginning of its return movement.
25. In a combined typewriting and com-

- puting machine, the combination with computing mechanism, of a letter-feeding carriage for determining the state of said computing mechanism, indexing devices, a power device for running into the computing mechanism the numbers indexed, and a second trip device controlled by said carriage for determining the activity of said power device, said trip devices being spaced apart a distance corresponding to the computing zone, said carriage acting on said state-control trip at the beginning of its movement into the computing zone, and acting on said power trip at the beginning of its return movement after completing its zonal movement.
26. In a combined typewriting and computing machine, the combination with computing mechanism, of a letter-feeding carriage, a member settable thereon, a trip device controlled by said carriage for determining the state of said computing mechanism, indexing devices, and a power device for running into the computing mechanism the numbers indexed, said carriage acting on said trip device through the medium of said settable member to control the state of said computing mechanism on a letter-feeding movement of said carriage, and acting to render said power device effective on the beginning of its return movement.
27. In a combined typewriting and computing machine, the combination with computing mechanism, of a letter-feeding carriage, a member settable thereon, a trip device controlled by said carriage for determining the state of said computing mechanism, indexing devices, a power device for running into the computing mechanism the numbers indexed, and a second trip device controlled by said carriage for determining the activity of said power device, said carriage acting on said state-control trip through the medium of said settable member on a stepping movement of said carriage, and acting on said power trip also through the medium of said member on its return movement.
28. In a combined typewriting and computing machine, the combination with computing mechanism, of a letter-feeding carriage, a tabulator stop therefor, a trip device controlled by said carriage for determining the state of said computing mechanism, indexing devices, a power device for running into the computing mechanism the numbers indexed, and a second trip device controlled by said carriage for determining the activity of said power device, said trip devices being spaced apart a distance corresponding to the computing zone, said carriage acting on said state-control trip through the medium of said tabulator stop at the beginning of its movement into the computing zone, as determined by said stop, and acting on said power trip through the medium of said tabulator stop on the beginning of its return movement after completing its zonal movement.
29. In a combined typewriting and computing machine, the combination with computing mechanism, of a letter-feeding carriage, a member settable thereon, indexing devices, a power device for running into the computing mechanism the numbers indexed, a trip device for determining the state of said computing mechanism, a second trip device for determining the activity of said power device, said settable member being reversible and acting when in one position to act on both of said trips, and when in the other position, acting on said power trip only.
30. In a combined typewriting and computing machine, the combination with computing mechanism, of a letter-feeding carriage, a member settable thereon, indexing mechanism, and a power device for running into the computing mechanism the numbers indexed, said settable member being reversible and acting when in one position to control the state of said computing mechanism and the effectiveness of said power device, and acting when in the other position to control the activity of said power device only.
31. In a combined typewriting and computing machine, the combination with a traveling carriage, and a plurality of computing devices, of indexing mechanism, a power device for running into the computing devices the numbers indexed, members settable on said carriage, and a single means common to said settable members for controlling the activity of said power device at the beginning of the return of the carriage immediately after writing the units digit of a number in any one of the computing columns.
32. In a combined typewriting and computing machine, the combination with computing mechanism, of a traveling carriage, an array of decimal stops for positioning said carriage, means effective at one end of the array of decimal stops for controlling the state of said computing mechanism, and means effective at the other end of the array of said decimal stops for controlling the activity of said computing mechanism.
33. In a combined typewriting and computing machine, the combination with computing mechanism, of a letter-feeding carriage, and means for determining on a letter-feeding movement of said carriage, whether the carriage shall, on its return movement, produce a change of state or not in said computing mechanism.
34. In a combined typewriting and computing machine, the combination with computing mechanism, of a letter-feeding car-

- riage, indexing mechanism for the computing mechanism, a general operator for running into the computing mechanism the numbers indexed, and means brought into 5 action at a letter-feeding movement of said carriage for changing the state of the computing mechanism, said carriage on its return movement causing said general operator to restore said computing mechanism 10 to its previous state.
35. In a combined typewriting and computing machine, the combination with computing mechanism, of a letter-feeding carriage, indexing mechanism for the computing mechanism, a general operator for running into the computing mechanism the numbers indexed, and a reversible member carried by said carriage, said member determining whether said general operator shall 15 change the state or not of said computing mechanism on a return movement of said carriage, depending on the position of said member on the stepping movement of said carriage.
- 20 36. In a combined typewriting and computing machine, the combination with computing mechanism, of a letter-feeding carriage, a reversible tabulator stop therefor, indexing mechanism for the computing 25 mechanism, and a general operator for running into the computing mechanism the numbers indexed, said tabulator stop determining by its position when stopping the carriage at the computing zone, whether said 30 general operator shall change the state of said computing mechanism or not on the return of the carriage from its passage through the computing zone.
37. In a combined typewriting and computing machine, the combination with computing mechanism, of a letter-feeding carriage, a tabulator stop for determining the computing zone of said carriage, and means 40 acting through the medium of said tabulator 45 stop for bringing said computing mechanism into action on the return of the carriage through the computing zone as determined by said stop.
38. In a combined typewriting and computing machine, the combination with computing mechanism having indexing devices, and means for running into the computing mechanism the numbers indexed, of a letter-feeding carriage, and a plurality of trips 50 for controlling said computing mechanism, one of said trips controlling the state of said computing mechanism, and the other of said trips controlling the running into said computing mechanism of the numbers indexed, 55 said carriage acting on the state-controlling 60 trip during a letter-feeding movement of said carriage, and acting on the other trip on the return movement of said carriage.
39. In a combined typewriting and computing machine, the combination with computing mechanism having indexing devices, and means for running into the computing mechanism the numbers indexed, of a letter-feeding carriage, and a plurality of trips for controlling said computing mechanism 65 through the medium of said carriage, said carriage acting on one of said trips at the beginning of the computing zone to control the state of the computing mechanism for that zone, and acting on the other of said 70 trips at the return movement of said carriage, after it has completed its movement through the computing zone, to run into the computing mechanism the number indexed. 75
40. In a combined typewriting and computing machine, the combination with computing mechanism having indexing devices, and means for running into the computing mechanism the numbers indexed, of a letter-feeding carriage, a member settable thereon, 80 and a plurality of trips for controlling said computing mechanism, said carriage acting on one of said trips on a letter-feeding movement of said carriage to control the state of said computing mechanism, and 85 acting on the other of said trips on the return movement of said carriage to control the running in of the number indexed, said carriage acting on said trips on both 90 said movements through the medium of said 95 settable member.
41. In a combined typewriting and computing machine, the combination with computing mechanism having indexing devices, and means for running into the computing 100 mechanism the numbers indexed, of a letter-feeding carriage, a tabulator stop therefor, and a plurality of trips for controlling said computing mechanism through the medium 105 of said carriage, said carriage acting on one of said trips at the beginning of the computing zone as determined by said stop, to determine the state of the computing mechanism for that zone, and acting on the other of said trips on the return movement of said 110 carriage, after it has completed its movement through the computing zone, to control the running in of the number indexed, said carriage acting on said trips on both said 115 movements through the medium of said tabulator stop.
